UNITED STATES PATENT OFFICE.

BARRETT ROGERS, OF BERWYN, ILLINOIS, ASSIGNOR TO BENJAMIN ELECTRIC MANUFACTURING COMPANY, OF CHICAGO, ILLINOIS, A CORPORATION OF ILLINOIS.

TWO-WAY PLUG.

Application filed September 16, 1921. Serial No. 501,163.

My invention relates to electrical connector devices, and more specifically to two-way plugs.

One of the objects of my invention is to provide an improved two-way plug which will be durable and efficient in use, simple in construction, cheap to manufacture and easy to assemble.

A further object of my invention is to provide a novel arrangement for spacing and insulating a metallic plug receptacle casing from the plug contacts.

Another object of my invention is to form a compact and rigid supporting and electrical connecting means for the plug receptacle contacts.

Another object of my invention is to provide a two-way plug, with metallic housing portions which may be permanently assembled and finished before inserting the contact members and their supporting means.

A further object of my invention is to provide an improved two-way plug in which the receptacle portion can be used as a sort of handle for frictionally screwing the plug portion into a socket, and in which, after the plug portion has been screwed home, the receptacle portion can be adjusted to any desired position, and in which the receptacle portion can be used as a handle for positively operating on the plug portion to unscrew it.

Further objects will appear from the detailed description to follow and from the appended claims.

In the drawings in which two embodiments of my invention are shown—

Figure 1 is a side elevation of a two-way plug;

Fig. 2 is a section substantially on the line 2—2 of Fig. 4;

Fig. 3 is a side elevation of the plug, parts being broken away to show the interior construction;

Fig. 4 is a part elevational, part sectional view, the sections being substantially on the line 4—4 of Fig. 3;

Fig. 5 is a bottom plan view of the plug;

Fig. 6 is a bottom plan view of the lower insulating base;

Fig. 7 is a perspective view of the device with the upper plug portion removed;

Fig. 8 is a section substantially on the line 8—8 of Fig. 4; and

Fig. 9 is a view of some of the parts before assembly.

Referring now to Figs. 1 to 9 inclusive, the two-way plug shown therein comprises plug shell and center contacts 10 and 11 respectively, shell receptacle contacts 12 and 13 respectively, center receptacle contact members 14 and 15 respectively, and suitable means for positioning, supporting and insulating the aforesaid contacts.

As indicated in the statement of the invention, a sort of ratchet connection is provided between the receptacle portion and the plug portion by means of which a frictional engagement is provided between the receptacle portion and the plug portion in using the receptacle portion to screw the plug portion into the socket and in which a positive engagement is provided between the receptacle portion and the plug portion when the receptacle portion is used as a handle for screwing the plug portion out of the socket. Details of this construction will be set forth hereinafter.

As set forth more fully hereinafter, means are provided whereby the receptacle contacts and the plug contacts and their immediate insulating members can be assembled after the casing for the receptacle contacts and associated parts have been assembled as a unitary device.

The center contact 11 is supported in position with respect to the plug shell contact 10 by means of a cylindrical insulating base 16. The receptacle contacts 12, 13, 14 and 15 are supported in position by means of an insulating base 17.

The insulating base 17 and the receptacle contacts are housed by means of a sheet metal housing member 18, formed of stamped or rolled sheet metal parts seamed together, as indicated at 19 and 20. The receptacle shell contact 13 has its axis parallel to the axis of the plug shell contact 10 but offset with respect thereto, and the inner end of the threaded shell contact 12 is located between the plug shell contact 10 and the receptacle shell contact 13. By this construction, the two-way plug can be screwed into a socket provided with a comparatively deep narrow shade, and one of the sockets will still be in position to hold a lamp with its axis parallel to the axis of the shade.

The two insulating bases 16 and 17 are secured together by means of a central screw 21, which extends through aligned openings in the insulating bases and is threaded into

a sheet metal stamping 22, the lower end of which forms the center contact member 15, and the upper end of which serves as a clamping member to hold the center contact member 14 in position. The central screw 21 serves also to electrically connect the plug center contact 11 with the receptacle center contacts.

The center contact member 15 is supported and insulated from the threaded shell contact 13 by means of an insulating disc 23 of fibre or the like. The shell receptacle contacts 12 and 13 are mounted on a pair of anchorage members 24, which anchorage members are in turn mounted on the insulating base 17. Each of these anchorage members 24 comprises a stamping of sheet material, having an upper foot portion 25, into which is threaded a screw 26 for securing the anchorage members 24 to the insulating base 17. Each stamping is also provided with a lower foot portion 27, into which is threaded a screw 28, for securing the shell receptacle contact 13 to the anchorage member, this screw 28 extending through an opening in the flange 29 of the threaded shell contact, and being threaded into the foot portion 27. Each of the anchorage members 24 is also provided with an inclined intermediate portion 30, to which the inwardly extending flange portion of the threaded shell receptacle contact 12 is secured by means of a screw 31 extending through the flange of the shell contact and threaded into the anchorage member.

The sheet metal casing 18 has an inwardly extending flange 32 at its upper end, which is clamped against the insulating base 17 by means of the central screw 21, an insulating washer 33 being provided to form a clamping member for the upper side. This clamping member also serves to help position the threaded shell plug contact 10 and insulate it from the casing 18.

As heretofore stated, means are provided whereby the threaded shell plug contact 10 is frictionally engaged to screw it into the socket, and is positively engaged to unscrew it from the socket.

For this purpose a ratchet member 34 (Fig. 9) is provided, which is secured to the insulating base 17 by means of the same screws 26 hereinbefore referred to which hold the anchorage members 24 in place, these screws extending through openings 35 in the ratchet member. This ratchet member 34 is provided with upwardly bent ratchet teeth 36, which engage ratchet openings 37 in the threaded shell plug contact 10, whereby the threaded shell contact can be positively unscrewed from the socket. The ratchet member 34 is also provided with a pair of upwardly bent spring fingers 38 which frictionally engage the flange 39 of the threaded shell contact 10 for screwing the

threaded shell contact into the socket. In order to hold the flange 39 of the threaded shell contact 10 down into proper engagement with the ratchet teeth 36 and the spring fingers 38, a corrugated annular spring 40 is provided, above the flange 39, inside the threaded shell contact, which bears down on this flange and holds it firmly in electrical and frictional engagement with the ratchet member 34. The upper face of this spring 40 is supported by the lower shoulder 41 of the insulating base 16.

It is to be noted that means are provided for preventing any relative rotation between the following parts which are connected together; the insulating base 17, the insulating base 16, the insulating washer 33, and the ratchet member 34. These parts are all connected together as a unitary device, the threaded shell plug contact 10, however, being swiveled about the insulating base 16, the flange 39 of this threaded shell contact being held in place and positioned between the insulating washer 33 and the corrugated annular spring 40. The means for preventing relative rotation between the parts referred to above are as follows; the insulating washer 33 is positioned on the insulating base 17 by means of a pair of bosses 42 on the insulating base 17 which extend into correspondingly-shaped openings 43 in the washer. The ratchet member 34 is positioned with respect to the washer 33 by the downwardly struck conical or countersunk portions 44 which extend into the countersunk openings 45 in the washer 33. The screws 26 which extend through registering openings in the ratchet member 34, the washer 33, and the insulating base 17 also serve to prevent relative rotation between these parts. The upper insulating base 16 is held against rotation with respect to the ratchet member 34 by means of a pair of upwardly extending projections 46 struck up from the material of the ratchet member, which engage notches 47 in the boss 48 on the lower face of the insulating base 16. This boss 48 also serves to space the insulating base 16 from the insulating base 17 to provide clearance for the inwardly extending flange 39 of the threaded shell contact, and for the corrugated spring 40 and the ratchet member 34. The bosses 42 on the insulating base 17 also serve to position the casing 18 by engagement with the openings 49 in the upper portion of the casing (Fig. 7).

Referring now to the manner in which the device is screwed in and out of the socket, in this operation the receptacle portion is used as a handle. In screwing the plug portion in there is a frictional engagement between the receptacle portion and plug shell, but in screwing the plug portion out there is positive engagement between the receptacle portion and plug shell.

This insures that one will be able to screw the plug portion out of the socket. In screwing the plug portion into the socket, using the receptacle portion as a handle, the threaded plug shell contact 10 is frictionally held between the corrugated washer 40 and the upwardly bent spring fingers 38, so that as the receptacle portion is rotated as a handle, the plug contact 10 will be screwed into the socket.

After the plug portion has been screwed home in the socket, the receptacle portion can be turned to any desired position to bring the laterally extending receptacle having the contact 12 to any desired position, suitable for the connection to be made. The plug portion, of course, will remain stationary during this adjustment of the receptacle portion, the frictional engagement permitting this adjustment.

To screw the plug portion out, the receptacle portion is rotated in a direction reverse to that in screwing the plug portion in. During this reverse rotation, the ratchet members 36 enter the ratchet openings 37 in the shell contact 10 and positively engage the shell contact 10 to unscrew it from the socket.

In assembling the two-way plug, the housing member 18 is first constructed as a unitary device by seaming the parts together at 19 and 20. The various parts are then assembled in and about this housing. The construction is such that the parts which are located inside the housing 18 can be inserted through the outer openings. The insulating base 17 and insulating washer 33 are first put in position to embrace between them the flange 32 of the housing. The ratchet member 34 is then placed in position on the insulating washer 33. The anchorage members 24 are then put in place, and the screws 26 are inserted and screwed into the anchorage members 24. The shell contact 12 may then be slipped into its insulating sleeve or cup 50, and secured to the anchorage members 24 by means of the screws 31. The shell receptacle contact 13 is then slipped into its insulating cup or sleeve 51 and secured by the screws 28. The insulating disc 23 is inserted into the contact 13, the stamping 22 is assembled with respect to the disc 23, threaded shell plug contact 10, corrugated washer 40, center contact 14 and insulating base 16 are assembled in proper position, and the central screw 21 is inserted into place and screwed into the stamping 22, to hold the parts in assembled position.

The advantage of assembling the inside construction of the receptacle part after the casing part is assembled and finished, is that it would be practically impossible to finish the casing after the inside construction was assembled, as the acid which is used in fin-

ishing would ruin the inside construction of the receptacle. It would be impracticable to seam the two parts of the casing together after they were finished as this operation would mar the finish. The ability to assemble the inside receptacle construction after the casing is finished has a special advantage in the metal casing construction.

Having thus described my invention, what I claim as new and desire to secure by Letters Patent of the United States is:

1. A plug receptacle comprising a plug portion and a receptacle portion, said plug portion comprising a center contact and a screw shell contact, said receptacle portion comprising receptacle contacts, said screw shell contact being swiveled with respect to said receptacle portion, and transmission means between said receptacle portion and screw shell contact, whereby said receptacle portion may be used as a handle in screwing the plug portion in or out with respect to a socket, said transmission means comprising a ratchet.

2. A plug receptacle comprising a plug portion and a receptacle portion, said plug portion comprising a center contact and a screw shell contact, said receptacle portion comprising receptacle contacts, said screw shell contact being swiveled with respect to said receptacle portion, and transmission means between said receptacle portion and screw shell contact, whereby said receptacle portion may be used as a handle in screwing the plug portion in or out with respect to a socket, said transmission means comprising a ratchet for turning said screw shell contact in one direction, and a spring for turning it in the other.

3. A plug receptacle comprising a plug portion and a receptacle portion, said plug portion comprising a center contact and a screw shell contact, said receptacle portion comprising receptacle contacts, said screw shell contact being swiveled with respect to said receptacle portion, and transmission means between said receptacle portion and screw shell contact, whereby said receptacle portion may be used as a handle in screwing the plug portion in or out with respect to a socket, said transmission means comprising means for positively turning said shell in one direction and means for incompletely turning it in the other direction.

4. A plug receptacle comprising a plug portion and a receptacle portion, said plug portion comprising a center contact and a screw shell contact having a flange, said receptacle portion comprising receptacle contacts, said screw shell contact being swiveled with respect to said receptacle portion, and transmission means between said receptacle portion and screw shell contact, whereby said receptacle portion may be used as a

- handle in screwing the plug portion in or out with respect to the socket, said transmission means comprising a spring bearing on said flange, and located inside said screw shell contact.
5. A plug receptacle comprising a plug portion and a receptacle portion, said plug portion comprising a center contact and a screw shell contact having a flange, said 10 receptacle portion comprising receptacle contacts, said screw shell contact being swiveled with respect to said receptacle portion, and transmission means between said 15 receptacle portion and screw shell contact, whereby said receptacle portion may be used as a handle in screwing the plug portion in or out with respect to the socket, said transmission means comprising a spring bearing on said flange, and a ratchet engaging said flange.
- 20

6. A plug receptacle comprising a plug portion and a receptacle portion, said plug portion comprising a center contact and a screw shell contact having a flange, said receptacle portion comprising receptacle contacts, said screw shell contact being 25 swiveled with respect to said receptacle portion, and transmission means between said receptacle portion and screw shell contact, whereby said receptacle portion may be used as a handle in screwing the plug portion 30 in or out with respect to the socket, said transmission means comprising a spring bearing on one side of said flange and pressing the other side of said flange into contact with a surface on said receptacle portion.

In witness whereof, I have hereunto subscribed my name.

BARRETT ROGERS.
